(57) **CLAIM**

The ornamental design for a teeth flushing device, as shown and described.

DESCRIPTION

FIG. 1 is a front, bottom and right side perspective view of a teeth flushing device showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged view of portion 8 in FIG. 1; and,

FIG. 9 is an enlarged view of portion 9 in FIG. 3.

1 Claim, 9 Drawing Sheets

FIG. 1

FIG. 2

FIG. 3

FIG. 4

FIG. 5

FIG. 6
